TOWEL RING BASE

Raymond U. H. Tegner, Lodi, Wis., assignor to
Amerock Corporation, Rockford, Ill.

Original design application Jan. 4, 1974, Ser. No.
430,938. Divided and this application Sept. 3, 1974,
Ser. No. 502,623

Term of patent 14 years

Int. Cl. D6—06; D8—08
U.S. Cl. D6—103

FIG. 2.

FIG. 3.

FIG. 4.

FIG. 5.

FIG. 1 is a front view of a towel ring base incorporating my new design.

FIG. 2 is a side view as seen from the right in FIG. 1.

FIG. 3 is a top view of the base.

FIG. 4 is a bottom view of the base.

FIG. 5 is a sectional view taken along the line 5—5 in FIG. 1.

This application is a division of my co-pending application Ser. No. 430,938, filed Jan. 4, 1974.

I claim:

The ornamental design for a towel ring base, as shown.
